UNITED STATES PATENT OFFICE.

MAX MAURAN, OF NIAGARA FALLS, NEW YORK.

DISCHARGING-VALVE FOR FLUID-HOLDING RECEPTACLES.

1,027,136.

Specification of Letters Patent.

Patented May 21, 1912.

Application filed April 8, 1911. Serial No. 619,711.

To all whom it may concern:

Be it known that I, MAX MAURAN, a citizen of the United States, residing at Niagara Falls, in the county of Niagara and State of New York, have invented certain new and useful Improvements in Discharging-Valves for Fluid-Holding Receptacles, of which the following is a full, clear, and exact description.

10 This invention relates to means for breaking or perforating the seals of receptacles, and more especially seals of the type disclosed in my co-pending application Serial No. 619,712, filed of even date herewith.

15 It further relates to a novel dispensing appliance.

It has heretofore been found exceedingly difficult to properly dispense fluids, especially where the latter are under high pressures, from receptacles which contain the same without involving considerable loss of such fluids; more particularly is this the case where it is intended to use but a fraction of the fluid in the receptacle at any one time.

20 25 In my said application I have disclosed a novel seal and means for forming the same; the apparatus therein described having been designated a charging valve.

The present invention involves, in combination with other elements, an apparatus which may be of somewhat similar construction to the seal forming appliance described in said application, and aims at overcoming the difficulties above referred to. These and 30 other objects of my invention will be herein-after set forth and more particularly pointed out in the appended claims.

I am aware that various modifications of the apparatus to which this application relates may be made without departing from the spirit of my invention, and I hence desire to be limited only by the scope of said 35 appended claims.

In the drawings which form a part hereof: Figure 1 is an elevation of my preferred form of apparatus. Fig. 2 is a longitudinal axial section of said apparatus. Fig. 3 is a fragmentary section illustrating the action of a perforating plunger used in the said 40 apparatus.

45 Referring to the drawings in which like characters designate like parts throughout the several views; a suitable casing 1 is chambered as at 2, such chamber being preferably circular in cross-section. The upper 50 end of the casing is counterbored as at 3 for the reception of suitable packing 4, the lat-

ter being held in position by a gland 5 in the usual manner. This packing is disposed around a preferably cylindrical plunger 6 which extends down into the chamber or cavity 2, and practically fills the same when the plunger is in its lowermost position. The upper end of the plunger is threaded as at 7 and has a hand-wheel 8 firmly mounted thereupon by means of which the plunger may be advanced into or retracted from the said chamber; the portion 7 being in threaded engagement with a gland retaining sleeve 9. This sleeve may be slotted as 10 at 10 for ventilation, to protect the threaded parts from any gases which might escape, and to facilitate turning the sleeve; and its lower end is preferably enlarged or headed as at 11 and apertured to receive the upper 15 end of the casing 1, with which it is in threaded engagement. The threaded connection 12, in question, is preferably made left handed to counteract the tendency, otherwise in evidence, of the plunger when 20 being rotated right hand and when therefore entering the cavity or chamber 2 to tighten the packing unnecessarily; and to counteract the possibility of unscrewing sleeve 9 and loosening packing 4, when with 25 drawing the plunger. The chamber 2 has, preferably, a single port 13 leading thereto, the casing having a laterally projecting arm 14 through which this port extends. Suitable means are provided in connection 30 with this arm for connecting the port therein with a tube 15, which serves to permit 35 of the withdrawal of fluid from the receptacle 16 to which the casing is affixed when 40 in operation, and in the manner hereinafter 45 to be described.

The connecting means just referred to 50 preferably consist of a gland 17 of steel, or the like, which has a threaded connection with the arm 14, and which thereby provides means for driving a conical head 18 of brass, or other suitable material, into the recessed or countersunk end of said arm, to effect a tight joint therewith. The head 18 is axially apertured and is preferably secured to the extremity of the tube 15 by being brazed thereto, if the said tube be 55 made of copper or the like. A coupling or nipple 19 is provided in connection with the receptacle and is preferably fixedly secured thereto and threaded exteriorly for connection with the lower end of casing 1, said end being counterbored and interiorly threaded for that purpose.

The lower or operative extremity of the plunger 6 is preferably reduced as at 20 and the lower extremity of this reduced portion preferably has the edges thereof relatively sharp to adapt the same to readily cut through the seal 21 of deformable material, which serves to plug or seal the vent in the receptacle in the manner shown in Fig. 2. The reduction of the plunger at its 10 extremity forms a seat or shoulder on the plunger, as at 22.

The foregoing apparatus constitutes a discharge valve and is designed to operate as follows: Assuming that the receptacle is 15 charged, or has been filled with fluid more or less under pressure and with its vent properly sealed. The discharge valve should be screwed in position upon the coupling or nipple and the tube 15 will be connected to the arm 14 in the manner above described. All connections having been made fast, the hand-wheel 8 may then be rotated clockwise as viewed from above, until the lower extremity of the plunger encounters 20 the lead seal. Continued rotation of said wheel will force the reduced end of the plunger into and through this seal, cutting a button therefrom and forcing said button through the vent or opening in the bottom 25 of the coupling; the body of the seal, however, being fixedly held in place in said coupling by reason of its engagement with the seat in the interior of the coupling. If now 30 the plunger be withdrawn by reversing the rotation of the hand-wheel 8, the fluid may then pass through the vent and through the aperture in the seal into the chamber 2, and thence out through the port 13 and through the tube 15 to the point 35 where it is intended to be used. Even though the pressure exerted by the fluid in the receptacle be very considerable, substantially no leakage will occur by reason of the packing around the plunger, nor around 40 the threads of coupling 19, which is prevented by the use of a suitable gasket 23 and further when it is desired to stop the flow of fluid from the receptacle it is merely necessary to again drive the plunger downwardly through chamber 2 until the seat 45 or shoulder 22 which is formed between the body of the plunger and its reduced portion, comes in contact with the deformable material of the seal which is disposed around the vent. The continued descent of 50 the plunger will then further force this material to conform to the shoulder 22 of the plunger and will hence provide a very effective temporary seal for the receptacle. 55 Of course the fluid may be withdrawn in any desired quantities and as often as desired, and the receptacle may be effectively

sealed after each withdrawal of fluid therefrom.

My apparatus is particularly adapted for 65 use in connection with such fluids as liquid chlorin, and, of course, the materials of which the respective parts are composed, should be adapted for use in connection with the fluid to be dispensed. For the seal forming material I find that lead is particularly well adapted, this metal being practically unacted upon by many chemically active fluids, while it possesses the requisite ductility to adapt it to be deformed and readily 70 perforated in the manner above described.

What I claim, is:—

1. The combination of a vented pressure fluid holding receptacle with a deformable seal therefor and an apparatus for manipulating the latter, said apparatus comprising a casing adapted to be secured to said receptacle at the vent thereof, a seal receiving part having a recess therein in communication with said vent, the bottom of 85 said recess forming a seat for the seal, said seal being of tenacious, ductile material and having a firm and close engagement with the lateral walls of said recess, and being securely held by such engagement against 90 outward displacement by the pressure of the fluid in said receptacle, said apparatus further comprising a plunger movable in said casing and adapted to deform said seal and open said vent. 95

2. The combination of a vented pressure fluid holding receptacle with a deformable seal therefor and an apparatus for manipulating the latter, said apparatus comprising a casing adapted to be secured to said 100 receptacle at the vent thereof, a seal receiving part having a recess therein in communication with said vent, the bottom of said recess forming a seat for the seal, said seal being of tenacious, ductile material and 105 having a firm and close engagement with the lateral walls of said recess, and being securely held by such engagement against outward displacement by the pressure of the fluid in said receptacle, said apparatus further comprising a plunger movable in 110 said casing and adapted to deform said seal and open said vent, said plunger having a portion thereof adapted for direct engagement with the so deformed seal to temporarily close said vent after the same has been 115 unsealed.

In witness whereof, I subscribe my signature, in the presence of two witnesses.

MAX MAURAN.
